(57) CLAIM

An ornamental design for a container closure, as shown and described.

DESCRIPTION

FIG. 1 is a perspective view of the subject container closure illustrating my new design;

FIG. 2 is a top view of the container closure;

FIG. 3 is a side view of the container closure; and,

FIG. 4 is a bottom view of the container closure.

The broken lines in FIG. 1 illustrating a perspective view of a top portion of a plastic container and a threaded container neck are for illustrative purposes only and form no part of the invention.
